UNITED STATES PATENT OFFICE.

WILLIAM BEDLE, OF KEYPORT, NEW JERSEY.

IMPROVED EXTENSION-TABLE.

Specification forming part of Letters Patent No. 53,774, dated April 10, 1866.

To all whom it may concern:

Be it known that I, WILLIAM BEDLE, of Keyport, county of Monmouth, and State of New Jersey, have invented a new and useful Extension-Table; and I do hereby declare the same is fully described and represented in the following specification and the accompanying drawings, of which—

Figure 1 is a top view of my invention in a folded state; Fig. 2, a top view as enlarged; Fig. 3, a top view with the center boards removed and the falling leaves raised, so as to form a round table; Fig. 4, a longitudinal section, showing the frame of table with drawer or box of same; Fig. 5, a transverse section, and Fig. 6 an under-side view of my multiform table.

The nature of my invention consists in so constructing or forming a table, simple, substantial, and compact, that the same shall be made to serve the purpose of side, breakfast, and dining table, as will be hereinafter explained.

In the drawings, A represents an ordinary frame-table having a box or stationary drawer, B, for reception of table-linen and dining utensils. C C are the sliding tops or leaves. D D are the falling leaves, which are hinged to the sliding tops. F is a bridge or brace for securing the frame, as well as for sustaining the slide-pieces G G which are firmly attached to and form part of the sliding tops.

The frame or box B has grooves C' C', in which the tongues d' d' of the sliding tops move, said tongues and grooves being intended to direct the longitudinal movements of the table-tops, as well as to sustain them when the table attains its greatest length, as shown in Figs. 2 and 4. H H, &c., are the removable tops, which may be of any desired number. h' h',

&c., are catches, which unite the said removable tops and falling leaves, and K K are brackets or slide-bars, which sustain the falling leaves when the table is used in the form shown in Fig. 3.

From the above description it will be seen that I have invented a very convenient table for families occupying limited dwellings, for while my table can be made to accommodate a large number at dinner, as shown in Fig. 2, it can, on the cloth being removed, be transformed into a round card or breakfast table, as shown in Fig. 3, and can also be made to assume the convenient form shown in Fig. 1 as a work-table to be placed by a window or in the corner of a room of limited dimensions.

It will be observed that the frame of my table is stationary and forms a drawer in the frame-work thereof, while the tops with their falling leaves slide on said frame, and in this respect differs essentially from the ordinary extension-table, where the frame-work with the end tops (being fastened together) extend by means of grooved bars which form part of the frame-work of same. I therefore do not claim the latter; but

What I do claim as my invention, and desire to secure by Letters Patent, is—

The leaves D D, falling parallel to the line of extension, when in combination with the sliding tops C C, the removable top or center boards, G G, and stationary box-frame, for the purposes set forth.

In testimony whereof I have hereunto set my signature.

WILLIAM BEDLE.
